LIQUID FUEL CONDITIONING MEANS

Harry B. Holthouse, Jr., Chicago, Ill., assignor to
 Galvin Manufacturing Corporation, Chicago,
 Ill., a corporation of Illinois

Application July 28, 1941, Serial No. 404,410

15 Claims. (Cl. 158—28)

This invention relates generally to means for treating liquid fuel in internal combustion heaters preliminary to the combustion thereof, and in particular to such means for an automobile heater of internal combustion type. This is a refined application for the application filed July 2, 1940, and given Serial No. 343,603.

It is an object of this invention to provide an improved means in internal combustion heaters for treating liquid fuel prior to its ignition.

Yet another object of this invention is to provide fuel conditioning means for a low pressure internal combustion heater which completely and uniformly vaporizes all of the fuel prior to its ignition.

A still further object of this invention is the provision of means for treating liquid fuel preliminary to its combustion in which the fuel is thoroughly mixed with air, vaporized and equalized as to density and pressure while being maintained at a substantially uniform temperature considerably below the ignition temperature of the fuel.

A feature of this invention is found in the provision of liquid fuel treating means for a heater of internal combustion type which is built as a separate and complete unit prior to its assembly in the heater.

Another feature of this invention is the provision of a liquid fuel vaporizing unit for a heater of internal combustion type in which a vertical heat conducting plate extending transversely of the unit and having a perforated top portion and an imperforate lower portion coacts with a heat conducting wall portion of the unit structure in forming a fuel trough at the bottom of the unit. Any fuel entering the unit which is not substantially immediately vaporized is collected in the trough and heated therein until it is completely vaporized so that only vaporous fuel is admitted into the combustion chamber of the heater.

A still further feature of this invention is the provision of a liquid fuel vaporizing unit for a heater of internal combustion type which is arranged adjacent the inlet of the heater combustion chamber, but which is insulated therefrom so that the fuel is completely conditioned at a temperature far below the igniting temperature of the fuel. Ignition of the fuel in the vaporizing unit is thus entirely prevented.

Another feature of this invention is the provision of a liquid fuel vaporizing unit for an internal combustion heater in which the fuel par-

ticles not immediately vaporized, are collected at the bottom of the unit in a fuel pocket and exposed to both heat and warm circulated supply air to assure their vaporization and passage from the unit in a vaporous form.

Further objects, advantages, and features of this invention will be apparent from the following description when taken in connection with the accompanying drawings in which:

10 Fig. 1 is a somewhat schematic illustration of an automobile heater of internal combustion type showing the arrangement therein of the improved liquid fuel treating means;

Fig. 2 is an enlarged detailed sectional view of the fuel treating unit shown in Fig. 1;

Fig. 3 is a transverse sectional view as seen along the line 3—3 in Fig. 2; and

Fig. 4 is a transverse sectional view as seen along the line 4—4 in Fig. 2.

20 The illustrated embodiment of the invention is shown as applied to an automobile heater of internal combustion type which is operable independently of the car engine and operated entirely by the electrical power from the car battery. Since the electrical power available from the usual car battery is relatively small, it is contemplated that the heater operating motor be of a size to operate on about 5 amperes of current, which is far below the average amperage

25 rating of a normal car battery and well within all practical factors of safety for heater current consumption. The use of a 5 ampere motor for operating the air and fuel supply means in the heater produces an air pressure in the heater

30 fuel conditioning unit of about $\frac{1}{8}$ of an inch to $\frac{1}{4}$ of an inch of water. Fuel cannot be properly atomized by an air pressure of this order so that air and fuel mixed at these pressures form what is commonly referred to as a "wet mixture."

35 Before this "wet mixture" can be efficiently burned it must be completely broken up and intimately mixed prior to ignition. The invention, therefore, contemplates the provision of means for uniformly and intimately mixing all 40 portions of the low pressure air and fuel preliminary to its combustion.

Referring to the drawings there is shown in Fig. 1 an automobile heater of internal combustion type which includes a housing structure 10 for a combustion chamber 11, an air supply chamber 12, an air supply fan 13, a fuel pump 14, an air circulating fan 16, and a motor 17; the motor being common in the operation of the fans 13 and 16 and fuel pump 14. The housing structure 10 45 has a longitudinally extending partition wall 18

which divides the housing into an upper compartment 19 and a lower compartment 21, the compartments 19 and 21 being in communication with each other through air passages 22 and 23. The combustion chamber 11 and air supply chamber 12 are of substantially cylindrical form and are assembled in axial alignment in the compartment 19, the chambers 11 and 12 being spaced away from the walls 18 and 24 of the housing 10 by radiating fins 26 to form an annular passage 27 about the combustion and air supply chambers.

Fan 16 operates to draw air into the heater through inlet 28 for circulation through the passages 23 and 27, the air being normally discharged from the heater through the outlet 29. The inlet 28 may be arranged to draw air into the heater from either the inside or outside of the car passenger compartment and the outlet 29 may be suitably connected to pass the heated air into the passenger compartment. The heated air may also be selectively controlled to be exhausted to the atmosphere or supplied to a windshield defroster or variably controlled therebetween. As illustrated in Fig. 1 this may be accomplished by a rotary valve 31 of disc form which is suitably supported in the housing 10. The valve is formed with apertures, such as 32, which are arranged in controlling relation to the passages leading to the atmosphere or to the defroster. In the illustrated position of the valve an aperture 32 is in alignment with a passage 33 leading to the atmosphere with a valve portion 34 covering the passage 36 leading to the defroster. The fan 13, which supplies air for combustion, has an inlet 37 open to the atmosphere which is suitably arranged in a wall portion of the motor compartment 38. Although the fuel pump 14 is shown as lying without the heater structure 10, it may be assembled within the motor compartment 38 so that the air entering the inlet 37 is circulated about the fuel pump 14 and motor 17 to cool these parts prior to its passage through the opening 22 into the air supply chamber 12. The fresh air supplied to the chamber 12 is thus initially heated by its circulation through the chamber 38, and is further heated by its counter-flow relation with the heated air passing through the annular passage 27. Air from the chamber 12 is mixed with the fuel from pump 14 in a fuel conditioning or treating unit 39 which is located within the chamber 12 and arranged at the inlet to the combustion chamber 11. The chamber 11 is of elongated construction having an outlet end (not shown) which is open to the atmosphere.

The unit 39 (Figs. 2, 3 and 4) includes an air and fuel mixing or vaporizing chamber 41 and an equalizing chamber 42, which are formed within a supporting shell or housing 43 of substantially cylindrical shape. As viewed in Fig. 2 the upper side of the housing 43 is of straight contour, while the lower side is of substantially stepped contour near the closed housing end 44 which is of reduced section. The stepped or wall portion 46 is located substantially opposite the air and fuel inlet 47 to the chamber 41, the unit outlet 48 being at the open end 49 of the housing 43. The inlet 47 is formed with a suitable mounting portion for a fuel nozzle 51 which is connected with the pump 14 through a supply line 52. The nozzle 51 is formed with apertures 53 which admit a portion of the supply air from the chamber 12 into the fuel stream from the fuel chamber 55 prior to the admission of the fuel into the vaporizing chamber 41. Another portion of the air from the

supply chamber 12 is admitted into the mixing chamber through air ports 54 which are formed in the unit housing 43. The ports 54 are suitably arranged about the nozzle 51 so as to direct the air into the partially broken up fuel stream on its ejection from the nozzle 51 into the chamber 41. The opposed disposition of the nozzle 51 and wall portion 46 causes the air and fuel mixture from the nozzle 51 and ports 54 to contact this wall, for a purpose to be later explained. A further portion of the air from the supply chamber 12 is admitted into the air and fuel mixture, after ignition thereof, through the air tube 40 which is supported in a wall portion of the combustion chamber 11. This additional air functions to lean the mixture after ignition to obtain a more complete burning thereof.

Chambers 41 and 42 are separated by a cup-shaped member 56 which is fitted into the housing 43 through the open end 49, the closed end 57 of the member 56 being positioned near the wall portion 46 and arranged transversely of the unit housing whereby to serve as a parting or partition wall between the chambers. The partition wall 57, as is best seen in Fig. 3, is formed over about its upper two-thirds portion with a plurality of apertures 58 which are in concentric arrangement. Approximately the lower third of the partition is imperforate so that communication between the chambers 41 and 42 is obtained only through the apertures 58. Positioning of the partition or dividing wall 57 near the wall portion 46 is determined by a pressed annular shoulder 59 formed in the housing 43, engagement of the shoulder with the cup 56 holding the cup in place in an obvious manner. The step 46 is inclined upwardly and away from the partition, as viewed in Fig. 2, to form a trough or pocket 61 between the step and imperforate bottom portion of the partition, for a purpose to be later explained. The open end of the cup member 56 is in abutting engagement with a heat insulating plate 62, which is positioned within the unit housing 43 from the end 49. As shown in Fig. 4, plate 62 is formed with a plurality of apertures 63 arranged in substantially a complete circle near its peripheral edge. Since in the heater arrangement of Fig. 1 the outlet 48 of the unit is positioned at the inlet 64 of the combustion chamber 11 the apertures 63 directly communicate the combustion chamber 11 with the equalizing chamber 42. The re-igniter element 66, which extends longitudinally outwardly of the unit 39, is mounted in the plate 62 in the upper portion thereof. The element 66 is composed of a suitable ceramic material and functions, as is well known, to maintain combustion in the chamber 11 after it has been started by other ignition means.

The ignition means of the present invention is formed as part of a combination preheating and igniting unit 67 which includes a resistance coil 68 arranged in an insulating tube 69, which in turn is mounted in a copper tubular sleeve 71. Element 67 is slantingly arranged longitudinally of the mixing chamber 41 and equalizing chamber 42 and is supported in the closed end 44 of the housing 43, and in the partition walls 57 and 62. The inclined wall portion or step 46 and the partition wall 57 are arranged in heat conducting relation with the element 67, the end 72 of which is formed to partially expose a portion of the resistance wire 68. That portion of the heating element 67 in the chambers 41 and 42 functions to heat the vaporizing unit 39, the unit housing

43 and the cup member 56 being provided in copper or other high heat conducting material to effect a rapid and uniform distribution of this heat throughout the unit. The element 67, therefore, does not operate as a hot spot but operates rather to heat the mixing and equalizing chambers and their surrounding walls to a substantially uniform temperature with the variation of the temperature within the chambers and their surrounding walls being about 10° F.

The chamber 42, which is defined by the partition walls 57 and 62 is filled with a copper wool or like material having high heat conducting characteristics which conducts heat from the heating element 67 into all portions of the chamber 42, whereby to heat all of the portions of the mixture entering the chamber 42 from the chamber 41, as will be explained. The unit 39 is thus seen to be completely preassembled prior to its installation in the heater apparatus illustrated in Fig. 1. This assembly of the liquid fuel conditioner 39 as a unit facilitates the mounting of the unit in the heater and makes it entirely accessible for any service work.

In the assembly of the unit 39 in the heater the end 72 of the heating element 67 is located at the inlet of the combustion chamber 11, the projection of heat from this end acting to ignite the fuel mixture entering the chamber. The heat thus projected is confined at the end 72 by the heat insulating partition 62, the degree of ignition heat being determined essentially by the length of the heating element and being contemplated in the present invention to be about 1800° F. The temperature in the mixing and equalizing chambers, however, is at all times less than that which would effect an ignition or burning of the fuel within such chambers, and is contemplated to be about 300° F. Thus, although the ignition temperature of the fuel is about 1800° F., the partition 62 substantially prevents this high heat in the combustion chamber 11 from being entirely transferred to the chambers of the vaporizing unit 39 so that the presence of an 1800° F. temperature on one side of the partition 62 occurs simultaneously with a temperature of only 300° F. on the opposite side thereof. This large difference between the optimum temperature within the vaporizing unit 39 and the ignition temperature within the combustion chamber 11 positively eliminates any burning of the fuel within the vaporizing unit 39.

A controlled heating of the unit 39 for advantageously vaporizing the fuel therein is accomplished by means of a thermal switch unit 73 (Fig. 1) which is responsive to the heat of the heating element 67 and acts to regulate the operation of such heating means. The unit 73 is mounted on, but electrically insulated from the element end 74 and extends into the air supply chamber 12; the unit being comprised of bi-metal contact arms 76 and 77 and associated contact arms 78 and 79, respectively. The bi-metal arms 76 and 77 are movable independently of each other and are adapted for movement at different temperatures; bi-metal switch 76-78 being in a normally closed position and arranged in the electrical circuit of the heating element 67, and bi-metal switch 77-79 being normally open and arranged in the electrical circuit of the fuel pump 14. Energization of the heating element 67 is obtained by connection thereof to a suitable electrical source such as the car battery 81, the circuit from the battery including conductors 82 and 83, bi-metal switch 76-78 and conductor 84;

the circuit being completed to ground by connection of the resistance wire 68 to the copper tubing 71 at the igniter end 72 of the unit 67. The conductors 82 and 83 are also common to the circuit of the fuel pump 14, which includes conductors 82 and 83, bi-metal switch 77-79, conductor 84, breaker assembly 85, and conductor 81. Motor 17 is connected directly to the battery 81 through conductors 82 and 83.

- 10 Operation of the heater unit 39 and hence of the heater apparatus is started by closing the main switch 89 which simultaneously operates the heating element 67 and fans 13 and 16; the circuit of the fuel pump 14 being opened by the normally open bi-metal switch 77-79. When the heating element 67 reaches a temperature of about 75° F., the bi-metal arm 77 moves into contact with the arm 79 to close the circuit of the fuel pump 14. The pump circuit is thus seen to be arranged to provide for the operation of the pump 14 only when the element 67 is in an operable condition. The air and fuel supplied to the chamber 41 by the fan 13 and fuel pump 14 through the ports 54 and fuel nozzle 51, respectively, contact the inclined wall portion or step 46 and that portion of the heater element 67 within the chamber 41. Since the wall 46 is at substantially the same temperature as the heating element 67 the fuel is partially vaporized by such contact so as to be intimately and thoroughly mixed with the air. The resultant mixture is forced through the apertures 58 in the partition wall 57 and thence into the equalizing chamber 42 by the pressure produced in the air supply chamber 12 by the air supply fan 13. From the equalizing chamber the mixture passes through the apertures 63 in the insulating partition 62 and into the combustion chamber 11, where it is ignited by the hot end 72 of the heating unit 67.
- 20 After combustion has thus been initiated the continued operation of the heater and heater element 67 serves to increase the temperature in the chambers 41 and 42. When the temperature in these chambers reaches a value of about 200° F., which represents a minimum operating temperature for advantageously conditioning the air and fuel for efficient combustion at low pressures, the bi-metal arm 76 moves out of engagement with the contact arm 78, to stop the operation of the heating element; the fans 13 and 16 and fuel pump 14 continuing in operation. At this operating temperature the fuel contacting the element 67 and the inclined wall 46 is substantially immediately vaporized by the heat in these parts; the angular inclination of the wall 46 with the heat conducting partition 57, which angle is about 45°, serving to deflect the mixture against the wall 57 to substantially completely vaporize all of the fuel supplied to the chamber 41. Any raw or free fuel particles which are not immediately vaporized by contact with the element 67 and walls 46 and 57 drop to the bottom of the chamber into the fuel cavity or trough 61. Since the fuel cavity is formed by the heated partition 57 and step 46 and further has the heating element 67 extending across the top thereof, the raw fuel collected therein is additionally heated. The fuel thus collected is exposed to the warm supply air circulating within the chamber 41 so as to facilitate its vaporization and passage into the chamber 42 through the apertures 58 in a vaporous form. Any unmixed or free fuel particles are thus retained in the chamber 41 until they are properly conditioned so that all of the fuel passing into the chamber 42 is in a vaporous form.

This vaporous form of the mixture continues in the chamber 42 due to its passage through the heated copper wool in the chamber; the wool acting further to diffuse all portions of the mixture to produce a mixture of substantially uniform fuel density. Since the mixture entering the chamber 42 through the apertures 58 tends to be somewhat turbulent in its flow the structure of chamber 42 acts further to equalize the velocity flow and pressure of the mixture over the entire transverse cross sectional area of the unit 39. The fuel mixture entering the combustion chamber 11 through the apertures 63 in the insulating partition 62 is thus of uniform consistency and is free of any isolated rich or lean portions, whereby combustion proceeds both quietly and efficiently. With the heater element 67 cut out by the operation of the bi-metal switch 76—78 the vaporous mixture is ignited by the igniter element 66, which is heated to a red glow during the initial combustion in the chamber 11.

The above described operating condition of the heater continues until the temperature in the chamber 41 falls below about 200° F., at which temperature the bi-metal arm 76 moves into contact with the contact arm 78 to again energize the heating element 67. When the temperature of the chamber 41 is again increased to about 200° F., the bi-metal arm 76 breaks away from the contact arm 78 to again open the circuit of the heater element 67. This controlled operation of the unit 39 continues during normal operation of the heater, the operation of the heater and hence of the unit being stopped by opening the switch 89.

During the normal operation of the heater a portion of the heat from the combustion chamber is transmitted through the walls of the housing structure 43 and also through the heater element 67 to the mixing chamber 41 and equalizing chamber 42. This transfer of heat decreases the dissipation of heat from the mixing chamber 41 by the cooling action of the vaporization of the fuel therein and decreases to some extent the effects of this cooling action on the element 67. The transfer of heat in this manner thus serves to reduce the frequency of operation of the heating element 67 by the thermal unit 73.

A "drifting" of the temperature in the mixing chamber is substantially eliminated by the location of the thermal unit on the element 67 and in the air supply chamber 12 since this location of the unit provides for an immediate control of the heater element in response to operating conditions in the chamber 41, and hence for a practically uniform operating temperature in mixing and equalizing chambers. It is to be understood, however, that the energization of the heating element 67 by the thermal unit 73 does not indicate a failure of combustion in the chamber 11. Energization of the heating element 67 may be the result of a sudden change in the temperature of the air and fuel entering the chamber. The mixture is processed independently of the burning conditions in the combustion chamber 11 and the bi-metal switch 73 operates to energize the heating element only in response to the temperature conditions in the mixing chamber 41.

In the passage of the mixture from the mixing chamber to the combustion chamber, the relative temperature difference between the heat conducting wool and the mixture in the chamber 42 is such that heat is transmitted from the wool

to the mixture to preserve its vaporous form. However, in the passage of a flame or a spark from the combustion chamber into the equalizing chamber the relative temperature difference between the combustion chamber and the equalizing chamber is such that heat is taken up by the copper wool so as to extinguish the flame or spark by reducing the temperature of the burning mixture below its ignition point. The equalizing chamber 42 thus acts to prevent any occurrence of "flashback" from the combustion chamber 11 into the conditioning unit 39.

The invention thus provides a means for conditioning liquid fuel preliminary to combustion which is positive and efficient in operation and which uniformly conditions the fuel regardless of the combustion conditions occurring in the combustion chamber. The unit 39 operates at all times to produce a vaporous mixture for burning in the combustion chamber 11 so that the condition of the mixture at the beginning of heater operation is substantially the same as its condition during normal heater operation. The cavity or trough 61 at the bottom of the mixing chamber effectively retains all raw fuel particles within the mixing chamber to prevent their passage into the equalizing chamber 42. Formation of the cavity by the heated partition 57 and inclined wall portion 46, and its location in proximity to the element 67 facilitates the vaporization of the fuel collected therein. The fuel within the cavity is further exposed to the heated supply air circulating in the chamber 41 so that the vaporized fuel is substantially immediately mixed with this air and carried through the apertures 58 into the equalizing chamber 42 in vaporous form. The fuel is thus positively ignited and completely burned at an even rate to substantially eliminate alternate periods of intense and low heat operation.

It is to be understood that only a preferred embodiment of the invention has been illustrated and described herein and that modifications and alterations thereof can be made which are within the full intended scope of the invention as defined by the appended claims.

I claim:

1. In a heater of internal combustion type, the combination of a combustion chamber, a liquid fuel vaporizing chamber in operative association with said combustion chamber, a vertical wall portion between said vaporizing and combustion chambers perforated over the upper portion and imperforate over the lower portion thereof, said vaporizing chamber having a wall portion adjacent to but inclined away from said vertical wall portion to form a fuel trough with said imperforate plate portion at the bottom of said vaporizing chamber, means for heating said vaporizing chamber, and means for supplying air and fuel to said vaporizing chamber, said fuel being directed toward said inclined wall portion and deflected against said vertical wall portion so as to be substantially completely vaporized prior to its passage out of said vaporizing chamber into said combustion chamber, with any raw particles of fuel being collected in said fuel trough to be heated and vaporized.

2. A preassembled liquid fuel vaporizing unit having an inlet and an outlet, a plate located between said inlet and outlet and extending transversely of said unit, said plate being perforated over the upper portion and imperforate at the lower portion thereof, with a wall portion for said unit having one end thereof spaced from

the lower imperforate portion of said plate to form a fuel retaining portion therebetween at the bottom of said unit, means for heating said unit, means for supplying air and fuel to said unit, with the fuel being directed toward said wall portion prior to its passage through the perforations in said plate, with the heat in said wall portion and plate acting to substantially completely vaporize said fuel, with the vaporous fuel passing through the perforations in said plate to said outlet, and any free fuel particles dropping into said fuel retaining portion to be heated and vaporized.

3. In a heater of internal combustion type, a liquid fuel vaporizing unit having an outlet, a heat conducting plate extending over substantially the entire cross section of said outlet, said plate being perforated over the upper portion and imperforate over the lower portion thereof, said unit having a heat conducting wall portion arranged relative to said partition to form a fuel pan therewith at the bottom of said unit, means for supplying air and fuel to said unit, means for heating said unit, said fuel being directed against said wall portion prior to its passage through the perforations in said plate so as to be substantially completely vaporized by the heat in said wall portion and plate, with any unvaporized fuel particles collecting in said pan to be heated and vaporized.

4. In a heater of internal combustion type, the combination of a combustion chamber, a liquid fuel vaporizing chamber having an inlet and an outlet, and substantially horizontally arranged in said heater with said outlet in communication with said combustion chamber, wall means over substantially the entire cross section of said outlet, said wall means being perforated over the upper portion and imperforate over the lower portion thereof, said vaporizing chamber having a wall portion opposite said inlet, adjacent said wall means forming a fuel pocket at the bottom of said chamber with said wall means, means for supplying air and fuel to said vaporizing chamber at said inlet, and means for heating said vaporizing chamber, said air and fuel being contacted against said wall portion and wall means, with the heat from these two parts acting to substantially completely vaporize the fuel prior to its passage through said perforations in said wall means into said combustion chamber, with any unvaporized fuel accumulating in said fuel pocket to be heated and vaporized.

5. In a heating device of internal combustion type, means for treating a liquid fuel prior to combustion including a fuel vaporizing unit having an inlet and an outlet, wall means arranged transversely of said unit between said inlet and said outlet having perforations over a portion thereof, said unit having a wall portion located relative to an unperforated portion of said wall means to form a fuel retaining portion therebetween, means for supplying air and fuel to said unit at said inlet, means for heating said unit, said fuel being substantially completely vaporized for mixing with said air by the heat from said wall portion and wall means prior to its passage through the perforations in said wall means to said outlet, with any raw fuel particles in said unit being received on said fuel retaining portion and heated for passage from said outlet in a vaporous form.

6. In a heater of internal combustion type having frame means, a preassembled unit sup-

ported on said frame means for treating liquid fuel prior to combustion, said unit being horizontally arranged in said heater and having one closed end with an inlet near said closed end and an outlet at said opposite end, a heat conducting plate apertured over an upper portion thereof extending transversely of said unit between said inlet and outlet, said unit having an inclined wall portion located substantially opposite said inlet and forming a fuel receptacle with said plate at the bottom of said unit, means for heating said unit, said heating means being supported in said closed end and plate and arranged between said inlet and inclined wall portion, and means for supplying air and fuel to said unit at said inlet, said fuel contacting said inclined wall and heating means to be substantially completely vaporized thereby prior to its passage to said outlet through the apertures in said plate, the unvaporized fuel particles dropping into said fuel receptacle to be additionally heated and vaporized for later passage to said outlet.

7. In a heater of internal combustion type, a liquid fuel vaporizing unit horizontally arranged in said heater and having an inlet and an outlet, a vertical partition extending over substantially the entire cross section of said outlet, said partition being perforated over the upper portion and imperforate over the lower portion thereof, said unit having a wall portion oppositely disposed from said inlet, with said wall portion being adjacent to said partition but inclined relative thereto to form a fuel pan at the bottom of said unit, means for supplying air and fuel to the unit at said inlet, means for heating said unit to at least a fuel vaporizing temperature, said fuel being directed against said wall portion and deflected therefrom against said partition so as to be substantially completely vaporized by the heat in such two parts prior to its passage through the perforations in said partition, the unvaporized fuel particles descending into said pan to be further heated and vaporized so that all of the fuel passing through said outlet will be in a vaporous form.

8. In a heater of internal combustion type, means for treating a liquid fuel prior to combustion including a longitudinally extending fuel vaporizing unit of substantially cylindrical shape having an inlet and an outlet, a vertical partition wall arranged transversely of said unit between said inlet and said outlet, with said wall being perforated over the upper portion, and imperforate over the lower portion thereof, said unit having a wall portion located opposite said inlet, said wall portion being near to but inclined away from said partition wall to form a fuel cavity at the bottom of said unit with the imperforate portion of said partition wall, means for supplying air and fuel to said unit at said inlet, means for heating said unit, said fuel being substantially completely vaporized by contact with said inclined wall and partition prior to its passage through the perforations in said partition to said outlet, with the unvaporized raw fuel dropping into said fuel cavity to be additionally heated and vaporized for later passage through the perforations in said partition wall, and means for conducting heat from said heating means into the vaporized fuel at said outlet to provide a vaporous mixture of substantially uniform fuel density over the entire cross section of said outlet.

9. In a heater of internal combustion type having frame means, a preassembled unit supported

on said frame means for treating fuel prior to its combustion, said unit being of hollow construction, closed at one end and open at its opposite end, a heat conducting plate extending transversely of said unit between said two ends, said plate having a plurality of apertures formed therein at its upper portion and being imperforate over the lower portion thereof, said unit having a wall portion near said closed end cooperating with said heat conducting plate to form a fuel receptacle at the bottom of said unit, means for heating said unit, located in said unit and supported in said closed end and heat conducting plate, and means for supplying air and fuel to said unit near said closed end, said fuel being substantially completely vaporized by said heating means for mixing with said air prior to its passage to said open end through said perforations, any unvaporized fuel particles dropping into said fuel receptacle to be additionally heated and vaporized for later passage through said perforations to said open end.

10. A preassembled liquid fuel vaporizing unit having an inlet and an outlet and a wall portion, wall means extended transversely of said unit intermediate said inlet and outlet having a passage portion for fluid-connecting said inlet and outlet and an imperforate portion arranged to form a liquid fuel receptacle portion with a wall portion of said unit, means supplying air and fuel to said unit at said inlet, and means for heating said unit to at least a fuel vaporizing temperature, with said fuel being substantially completely vaporized by the heat adjacent said inlet for mixing together with said air so that a substantially vaporous mixture is admitted through said passage portion to said outlet, with any raw fuel particles not initially vaporized in said unit adjacent said inlet being retained in said liquid fuel receptacle portion and heated to a vaporizing temperature for passing to said outlet in a vaporous condition.

11. In a heater of internal combustion type, the combination of a chamber for mixing air and fuel for burning, means for supplying air and fuel to said chamber, a heating unit positioned in said mixing chamber and in contact with the air and fuel admitted thereto, with heating of said fuel by said heating unit preparing said fuel for mixing with said air, said chamber having a liquid fuel retaining portion at the bottom thereof for collecting any unmixed fuel particles, with said liquid fuel retaining portion having wall portions thereof thermally connected with said heating unit so that the heat from said wall portions vaporizes said unmixed particles for mixing with the air in said chamber, an energizing circuit for said heating unit, and thermostatic means in said circuit responsive in operation to the temperature conditions of said heating unit to control the energization of said circuit.

12. In a heater of internal combustion type having an operating circuit, the combination of a part thereof for mixing air and fuel, means supplying air and fuel to said part, means for heating the air and fuel in said part preparatory for burning the mixture thereof, said part having a liquid fuel retaining portion therein for collecting any unmixed fuel particles, with said liquid fuel retaining portion having a wall portion in thermal conductivity with said heating means so that the heat from said wall portion acts on said unmixed particles to vaporize the same for mixing with the air in said part, and

thermostatic means responsive in operation to the temperature conditions of and mounted on said heating means and connected in said heater operating circuit to effect operation thereof.

13. In a unit heater of internal combustion type for an automobile having a battery and a passenger compartment, the combination of a combustion chamber and an air and fuel mixing chamber operatively associated with said combustion chamber, said mixing chamber having a cavity at the bottom thereof, electrically operated means for circulating air from said passenger compartment about said combustion chamber, electrical means for supplying air and fuel to said mixing chamber, electrical heating means in said mixing chamber for heating the same to a predetermined optimum temperature to vaporize the fuel supplied thereto, said cavity having the walls thereof thermally connected with said electrical heating means, and said electrical heating means having an end portion thereof extending outwardly from said mixing chamber, any unmixed fuel being retained in said cavity and heated by the walls thereof for later passage to the combustion chamber in a vaporous form, and thermal means including a pair of bi-metallic switches mounted on said end portion and responsive in operation to the temperature condition of said heating means, with one of said switches controlling the operation of said heating means and the other of said switches the operation of said fuel supply means, all of said electrical means being operated by the electrical power from said battery.

14. In a heater of internal combustion type, the combination of a combustion chamber, a horizontally arranged unit for treating liquid fuel having an inlet at the top and an outlet at one end thereof, with said outlet being in communication with said combustion chamber, means for supplying air and fuel to said unit at said inlet, heat conducting means extending transversely of said unit between said inlet and outlet, said heat conducting means being perforated over a portion thereof, a heat conducting wall portion in said unit to provide a fuel pocket at the bottom of said unit between said wall portion and an imperforate portion of said heat conducting means, means for heating said unit to at least a fuel vaporizing temperature, said fuel being substantially completely vaporized for mixing together with said air by the heat from said wall portion and heat conducting means, said fuel pocket retaining any raw fuel particles in said unit until they are sufficiently heated to pass through the perforated portion of said heat conducting means in a vaporized form, and perforated heat insulating means extending transversely of the unit at said outlet to retain the heat of said combustion chamber away from the mixture in said unit.

15. In a heater of internal combustion type, the combination of a combustion chamber, a unit for treating liquid fuel preliminary to combustion having a heat conducting housing, said unit being closed at one end and having an open end in communication with said combustion chamber, a heat conducting member having perforations over a portion thereof extending transversely of said unit between said two ends, said unit having a wall portion at said closed end forming a fuel retaining portion at the bottom of said unit with an imperforate portion of said member, means for heating said unit supported in said closed end and heat conducting

member, means for supplying air and fuel to said unit at said closed end, said fuel being directed toward said heating means and substantially completely vaporized by the heat from said heating means and heat conducting member prior to its passage through the perforations in said member, with said fuel retaining portion retaining any raw fuel particles within said unit until they are sufficiently heated to pass through

5 said perforations in a vaporized form, perforated heat insulating means extending transversely of said unit at said open end to retain the heat in said combustion chamber away from the mixture in said unit, and igniting means mounted in said heat insulating means and extending into said combustion chamber.
